DESIGN FOR A STRAW HELMET HAT

Alfons Uriwal, Laredo, Tex., assignor to Texas
Harvest Hat Company, Inc., Laredo, Tex.

Application August 24, 1934, Serial No. 53,038

Term of patent 14 years

To all whom it may concern:

Be it known that I, ALFONS URIWAL, a citizen of the United States, residing at Laredo, in the county of Webb and State of Texas, have invented a new, original, and ornamental Design for Straw Helmet Hats, of which the following is a specification, reference being had to the accompanying drawing, forming part thereof.

Fig. 1 is a side elevational view of a hat showing my new design.

Fig. 2 is a bottom view of the same.

Fig. 3 is a top plan view of the same.

I claim:

The ornamental design for a straw helmet hat as shown.

In testimony whereof I have affixed my signature.

ALFONS URIWAL.
